UNITED STATES PATENT OFFICE.

CHARLES J. MEANS, OF BOSTON, MASSACHUSETTS.

CIRCUIT-CLOSER FOR ELECTRIC RAILROAD-SIGNALS.

SPECIFICATION forming part of Letters Patent No. 239,107, dated March 22, 1881.

Application filed January 3, 1881. (Model.)

To all whom it may concern:

Be it known that I, CHARLES J. MEANS, of Boston, in the county of Suffolk and State of Massachusetts, have invented a new and useful Improvement in Circuit-Closers for Electric Railroad-Signals, of which the following is a specification, reference being had to the accompanying drawings.

This invention relates to that class of circuit-closers in which the circuit is closed by the electrical contact of the wheels of a passing train with a metallic bar arranged by the side of and parallel to the rails, said bar being connected to one end of an electric circuit whose other end is grounded. It is desirable that this circuit-closing bar, in order to insure its being always in the proper position to make proper contact with the wheels of a train, should be elastic or yielding, and this has heretofore been effected by supporting each extremity of the bar upon a block of insulating material and depending upon the elasticity of the bar to return it to its normal position after being depressed. I have found, however, in practice, that with this arrangement the elasticity of the bar is not permanent, as it becomes bent or sagged by the frequent pressure of the wheels of passing trains.

The object of my present invention is to render such contact-bar permanently yielding throughout its entire length, and yet always insure its return to its normal position after its depression. I accomplish this by firmly securing to the contact-bar, at intervals throughout its entire length, metallic spring-bars, as hereinafter more fully set forth, which allow the bar to yield to the wheels of a passing train, and yet are so arranged that there is no possibility of their becoming permanently sagged or bent. The bars of metal also serve another purpose. By presenting considerable surface to the earth they form a partial ground, by which all currents of atmospheric electricity escape to the ground without injuring the magnets of the signaling-instrument in the circuit. There will not, however, be sufficient escape of the low-tension battery-currents to affect the apparatus.

In the accompanying drawings, Figure 1 is a top plan of the apparatus, and Fig. 2 is a section of the same through the line *x x*, in larger size.

Referring to these figures, A is a steel contact-bar about nine feet long, one and one-half inch wide, and one-fourth inch thick.

B B' B² B³, &c., are right-angled steel bars, of similar metal to the bar A, the short legs of which are riveted to the bar A by rivets *aa*. The other extremities are bolted to the under side of a two-inch plank, C, which extends the entire length of the bar A.

D D' are blocks of wood or metal, which support the plank C, and are of sufficient height to bring the top of the bar A about one-fourth inch above the top of the rail E.

It will be seen that by this arrangement the length of the bars B B', &c., will allow the contact-bar to yield as the wheels of a train pass over it and take the position shown by the dotted lines in Fig. 2, thus dispensing with the use of rubber or other springs.

The operation of the apparatus is as follows: The wheels of a passing train, rubbing along the top of the steel contact-bar A, make an electrical connection of the wheel and bar that closes the electric circuit, the wire *b* from the signaling-instrument being connected with the bar, and the current passing by said wire to the bar, wheel, rail, and ground.

Having thus described my invention, what I claim, and desire to secure by Letters Patent of the United States, is—

In a circuit-closer for railroads, the combination, with a long metallic bar, A, adapted to make electrical connection with the wheels of a car, of the shorter spring-bars B B' B² B³ B⁴, substantially as and for the purpose set forth.

Signed by me this 24th day of December, A. D. 1880.

CHARLES J. MEANS.
